(57) **CLAIM**

The ornamental design for a magnetic key organizer, as shown and described.

DESCRIPTION

FIG. 1 is an isometric view of the claimed magnetic key organizer, embodying the present design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof; and,

FIG. 8 is another isometric view of the magnetic key organizer in an open configuration.
